UNITED STATES PATENT OFFICE.

JOHN ROGERS, MADISON, WISCONSIN, ASSIGNOR TO JOHN GREGORY MCKENNA, OF MADISON, WISCONSIN.

AUTOMATIC LOCK FOR SWITCHES.

1,119,641.

Specification of Letters Patent.

Patented Dec. 1, 1914.

Application filed March 27, 1914. Serial No. 827,638.

To all whom it may concern:

Be it known that I, JOHN ROGERS, a citizen of the United States, residing at Madison, in the county of Dane and State of Wisconsin, have invented a new and useful Automatic Lock for Switches, of which the following is a specification.

The invention relates to automatic lock for railway switches.

10 The object of the present invention is to improve the construction of locks for railway switches, and to provide a simple, practical, and efficient lock of strong and durable construction, adapted to be readily applied to switch stands, and capable of enabling the switch operating lever to be released by a simple insertion of a key without turning the latter, whereby the operation of switching may be performed with great 20 rapidity and ease.

With these and other objects in view the invention consists in the construction and novel combination of parts hereinafter fully described, illustrated in the accompanying 25 drawing, and pointed out in the claims hereto appended, it being understood that various changes in the form, proportion, size and minor details of construction, within the scope of the claims, may be resorted 30 to without departing from the spirit or sacrificing any of the advantages of the invention.

In the drawing: Figure 1 is a plan view of a switch stand provided with automatic locks constructed in accordance with this invention, the switch shaft being shown in section. Fig. 2 is a side elevation of the same. Fig. 3 is a horizontal sectional view on the line 3—3 of Fig. 2, the table being shown in 40 reverse plan view. Fig. 4 is a vertical sectional view on the line 4—4 of Fig. 1. Fig. 5 is a detail horizontal sectional view on the line 5—5 of Fig. 4. Fig. 6 is a detail vertical sectional view on the line 6—6 of Fig. 5. Fig. 7 is a detail horizontal sectional view 45 similar to Fig. 5, showing the locking mechanism in a different position. Fig. 8 is a detail perspective view of the latch lever. Fig. 9 is a detail view of the key.

50 Like numerals of reference designate corresponding parts in all the figures of the drawing.

In the accompanying drawing, in which is illustrated the preferred embodiment of the invention, 1 designates a switch stand

table of segmental form, provided at its periphery with spaced notches 2 and 3, adapted to receive an outer pivoted arm 4 of an operating lever. The arm 4, which is provided at its outer end with a suitable grip 60 or handle, is pivoted at its inner end by a bolt 5 or other suitable fastening means to an inner arm 6, which is suitably fixed to a vertical switch shaft 7. The inner and outer arms 4 and 6 constitute the operating lever, 65 which is adapted to partially rotate the switch shaft 7 to operate the switch in the usual manner. The table 1 is designed to constitute the fixed top portion of an ordinary switch stand, and the shaft 7 is to be 70 connected with the ordinary switch mechanism (not shown), but as such construction is well known in the art, illustration thereof is deemed unnecessary. The inner arm 6, which is constructed of metal, is approximately 75 U-shaped in cross section, the pivoted end of the arm 4 being arranged between the sides of the arm 6. The pivoted end of the arm 4 is rounded at the upper outer corner 8 to enable it to clear the top wall or portion of the inner arm when the outer arm is 80 swung upwardly and outwardly from a vertical position to a horizontal position. The upward and outward swinging of the arm 4 carries the latter out of the notches of the 85 table 1, and arranges said outer arm 4 above the table and in longitudinal alinement with the inner arm 6. The operating lever may then be oscillated between the notches 2 and 3 to partially rotate the shaft 7. 90

The table 1 is equipped at each of the notches with a lock consisting of an approximately L-shaped latch lever 9, pivotally mounted within the casing 10, and carrying the locking lever 11, which engages 95 an interior shoulder 12 of the casing to retain the latch lever in its engaging position, with its engaging arm 13 extending across the outer end of its respective notch of the table 1 to confine the pivoted arm 4 therein, 100 as clearly illustrated in Fig. 5 of the drawing. The other arm 14 of the latch lever is hollow and is pivoted at a point intermediate of its ends by a vertical bolt or screw 15, and the said arm 14 extends longitudinally 105 of the casing at one side of the notch of the table when the latch lever is in its closed or engaging position. The locking lever is pivoted at a point intermediate of its ends within the hollow arm 14 by a pin 16, and 110

its inner or rear portion extends beyond the hollow pivoted arm 14 of the latch lever when the same is closed. The locking lever is maintained in engagement with the shoulder 12 by a spring 17 consisting of a central coil and terminal arms or portions, the coil being arranged on the pivot 15 and the said terminal portions of the spring engaging the pivoted arm 14 of the latch lever and the rear arm of the locking lever.

The locking lever 11 is substantially U-shaped in cross section, and its sides or flanges are provided at its front arm with recesses 18, adapted to interlock with a lug 19 of a key 20 when the latter is introduced into the casing of the lock. The key is provided with a rounded head beveled or cut away at the back at 21 to form a wedge-shaped portion which engages the front arm of the locking lever 11 and forces the same away from the adjacent portion of the latch lever to carry the rear arm of the locking lever out of engagement with the shoulder 12 of the lock casing. The front arm 25 of the locking lever bears against one of the walls of the hollow arm, adjacent to the inner end of the engaging arm 13 of the latch lever, and when the key is inserted in the lock casing, the lug 19 fits in the recesses 18 and interlocks the key with the locking lever. When the rear end of the locking lever is carried out of engagement with the shoulder 12 of the casing, the latch lever is free to swing on its pivot, and the pivoted arm 4 of the operating lever of the switch may be then swung out of the notch of the table 1. The outward swinging of the arm 4 oscillates the latch lever and moves the engaging arm 13 inwardly with respect to the casing and causes the rear portion of the pivoted arm to project into the notch of the table, as illustrated in Fig. 7 of the drawing. The projecting portion of the pivoted arm of the latch lever is then arranged in the path 45 of the arm 4 of the operating lever, and is adapted to be engaged by the same when the said arm 4 is swung downwardly and inwardly and returned to the notch of the table 1. The arm 4 returns the latch lever 50 to its engaging position, carrying the arm 13 across the front end of the notch after the said arm 4 has passed into the same. As it is only necessary to introduce the key into the lock casing to release the operating lever 55 of the switch, it will be seen that switching operations may be performed with greater rapidity and ease than is possible where locks are employed which require a key to be turned to lock or unlock the operating lever.

60 When the key is removed from the lock casing while the latch lever is in its open position, the locking lever is released and is adapted to automatically engage with the shoulder 12 when the latch lever is returned 65 to its engaging position, so that the lock is

entirely automatic and does not require the use of the key in returning the pivoted arm 4 to the notch of the table 1. The lock casing, which is secured to the lower face of the table, projects in advance of the same at 70 one side of the notch, and the outwardly projecting portion has an inclined upper face 22 and it is provided with a horizontal slot 23 connecting two key holes or openings 24 and 25 arranged to permit the key to be introduced into or released from the lock when the latch lever is in either of its positions. The latch casing is provided at the opening 23 with a flange 26 forming a guide to enable the key to be readily introduced into the lock. Ordinarily, in the use of the device, it is only necessary to introduce the key into the opening 24, the opening 25 permitting the removal of the key from the lock after the arm 4 has been swung out of the 85 notch of the table. The inner side of the casing is open and is located at one side of its respective notch of the table to permit either form of the latch lever to project at the said notch.

What is claimed is:

1. An automatic lock for switch stands including a pivotally mounted substantially L-shaped latch lever adapted to be oscillated to carry one of its arms to and from the notch of a switch stand, a locking lever carried by the latch lever and arranged to maintain the same normally in its engaging position, said latch lever and locking lever being arranged to permit a key to be interposed between them to carry the locking lever out of its engaging position.

2. An automatic lock for switch stands including a substantially L-shaped latch lever having a hollow pivotally mounted arm and adapted to oscillate to carry its other arm to and from the notch of a switch stand, a locking lever pivotally mounted within the hollow arm of the latch lever and arranged to maintain the same normally in its engaging position, said hollow arm being adapted to receive a key to permit the same to be interposed between the said levers to oscillate the locking lever and thereby release the latch lever.

3. An automatic lock for switch stands including a casing having an interior shoulder and designed to be mounted on a switch stand adjacent to a notch thereof, a substantially L-shaped latch lever pivotally mounted within the casing and adapted to be oscillated to carry one of its arms to and from the notch of the switch stand, a locking lever pivotally mounted on the latch lever and arranged to engage the shoulder of the casing, said levers being constructed to permit a key to be interposed between them to swing the locking lever out of engagement with the shoulder of the casing.

4. An automatic lock for switch stands

including a casing designed to be secured to a switch stand adjacent to the notch thereof and provided with spaced key holes, and having a connecting slot, a latch lever pivotally mounted within the casing and adapted to project at the said notch, a locking lever carried by the latch lever and arranged to engage the casing to retain the latch lever in its projecting or engaging position, said levers being arranged to permit a key to be interposed between them to oscillate the locking lever and thereby release the latch lever.

5. An automatic lock for switch stands including a casing designed to be mounted on a switch stand and provided with a projecting front portion having a beveled upper face and provided below the same with spaced key holes, and a connecting slot, a latch lever pivotally mounted within the casing and arranged to project therefrom to confine the operating lever in a notch of the switch stand, and a spring actuated locking lever mounted on and carried by the latch lever and arranged to engage the casing to retain the latch lever in its projecting or engaging position, said latch and locking levers being adapted to have a key interposed between them to oscillate the locking lever and release the latch lever.

6. An automatic lock for switch stands including a pivotally mounted approximately L-shaped latch lever having an engaging arm adapted to project at a notch of a switch stand, the other arm of the lever being hollow, a spring actuated locking lever mounted within the hollow arm and arranged to maintain the latch lever in its projecting or engaging position, said locking lever being provided with a recess arranged opposite a portion of the latch lever and adapted to interlock with a lug of a key to retain the same in the hollow arm.

7. The combination with a switch stand table having a notch, and an operating lever provided with an arm movable into and out

of the notch, of an automatic lock including a lever pivoted at an intermediate point and adapted to be oscillated to cause either of its terminal portions to project at the said notch, and a key controlled locking lever for normally maintaining the latch lever in one of its positions.

8. The combination with a switch stand table having a notch, and an operating lever provided with an arm movable into and out of the notch, of an automatic lock including a substantially L-shaped latch lever pivoted at a point intermediate of the ends of one of its arms adjacent to the said notch, the front arm being rounded to project at the front of the notch to retain said arm of the locking lever therein, said latch lever being adapted to oscillate to retract its engaging arm and to cause the terminal portion of its pivoted arm to project at the rear portion of the said notch, and a key controlled locking lever arranged to maintain the latch lever normally in a position with its engaging arm projecting at the front of the notch.

9. The combination with a switch stand having a notch and an operating lever provided with an arm movable into and out of the notch, of an automatic lock including a latch lever having angularly related arms and adapted to be oscillated to cause either of its arms to project at the said notch, one of the arms being adapted to confine the operating lever in the notch, and the other arm being arranged to be engaged by the operating lever to swing the latch lever to its engaging position, and key controlling locking means for normally maintaining the latch lever in its engaging position.

In testimony, that I claim the foregoing as my own, I have hereto affixed my signature in the presence of two witnesses.

JOHN ROGERS.
